(57) **CLAIM**

The ornamental design for a cover, as shown and described.

DESCRIPTION

FIG. 1 is a top, front, right side perspective view showing our new design for a cover.

FIG. 2 is a bottom, front, right side perspective view thereof. FIG. 3 is front view thereof, the back thereof being a mirror image.

FIG. 4 is a right side view thereof, the left side thereof being a mirror image.

FIG. 5 is a top view thereof.

FIG. 6 is a bottom view thereof.

FIG. 7 is a top, front, right side perspective view showing a second embodiment thereof.

FIG. 8 is a front view thereof, the back thereof being a mirror image.

FIG. 9 is a right side view thereof, the left side thereof being a mirror image; and,

FIG. 10 is a bottom view thereof, the top thereof corresponding to FIG. 5.

The broken lines adjacent the shaded areas represent the boundaries of the claimed design, while the other broken lines depict environmental subject matter only, and form no part of the claimed design.
